(57) **CLAIM**

The ornamental design for a toy model, as shown and described.

DESCRIPTION

FIG. 1 is a front, left and top perspective view of a toy model, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 1 thereof;

FIG. 10 is an enlarged view of portion of FIG. 1 thereof; and,

FIG. 11 is an enlarged view of portion of FIG. 2 thereof.

The dot-dash broken lines depict the boundaries of the enlargements that form no part of the claimed design.

The broken lines shown in the drawings illustrate portions of the toy model that form no part of the claimed design.

1 Claim, 11 Drawing Sheets
